UNITED STATES PATENT OFFICE.

DIEGO MATTEI, OF GENOA, ITALY.

APPARATUS FOR DYEING CARD-SLIVERS.

SPECIFICATION forming part of Letters Patent No. 746,863, dated December 15, 1903.

Application filed March 17, 1903. Serial No. 148,250. (No model.)

To all whom it may concern:

Be it known that I, DIEGO MATTEI, mechanical engineer, a subject of the King of Italy, residing at 22 Via Almeria, Genoa, Italy, 5 have invented certain new and useful Improvements in Apparatus for Dyeing Card-Slivers; and I do hereby declare the following to be a full, clear, and exact description of the invention, such as will enable others skilled in the art to which it appertains to make and use the same.

My invention refers to certain improvements in the apparatus for dyeing card-slivers, forming the object of my Patent No. 15 705,856. Said improvements are designed to obtain an apparatus as efficient as that protected by the aforesaid patent in as far as concerns the continuous impregnations of the cotton slivers with liquid and the dripping of 20 the impregnated cotton into the dye-baths without the slivers becoming disaggregated by the action of viscous or high alkaline baths. According to my aforesaid patent this difficulty is met by the use of perforated carrier-belts, which support the sliver during the 25 whole of the dyeing operations, relieving any stress therefrom. The provision of the said carrier-belts is practically efficient, but renders the machine to a certain extent expensive and complicated. By the employment 30 of the present improvements the said carrier-belts in the dye-vats are entirely done away with and the machine rendered thereby much simpler and cheaper. In order to describe 35 the same, it will be well to review the different operations which are to be performed in order to carry out the dyeing of the cotton slivers. They are as follows: first, impregnating the slivers with water or dye; second, 40 squeezing the same to expel said water or dye; third, dipping the sliver into a dye-bath if the sliver was previously impregnated with water; fourth, conveying the sliver and collecting the same, impregnated with dye, 45 into receptacles which may be heated by steam or contain a dye in order to fix the dye upon the fiber, and guiding said sliver to devices adapted to again impregnate, squeeze, and convey the same in order to repeat the same 50 operations as set forth under headings second, third, and fourth as many times as are necessary, according to the number of baths which

the sliver is to go through, depending upon the shade of the color which is to be imparted thereto; fifth, washing and finally squeezing and winding the sliver in the form of disks or cheeses.

In the accompanying drawings, in which I have illustrated an embodiment of my invention, and in which like reference characters 60 indicate similar parts throughout, Figure 1 is a plan view showing the general arrangement of the apparatus. Fig. 2 is a front elevation of Fig. 1. Figs. 3, 4, and 5 are side views of different sections of the apparatus. 65 Figs. 6 and 7 are longitudinal and transverse sections of a form of injecting device. Figs. 8 and 9 are longitudinal and transverse sections of a modified form of impregnating device. Figs. 10 and 11 are longitudinal and 70 transverse sections of a dyeing-tank. Figs. 12, 13, and 14 are an elevation and sectional detail view of the conveyer. Fig. 15 represents in detail the clutch mechanism; and Figs. 16 and 17 represent, respectively, an 75 elevation and a detail view of the stop-motion device.

Impregnation.—The impregnation is carried out in different ways, depending upon its taking place either with water and with 80 liquids which may be used in excess, or with liquids which are so expensive as not to allow of their being used in a greater quantity than strictly required. In the first case the injector intended to carry out the impregnation, Figs. 6 and 7, consists of a hollow cylinder 1, provided with only one bottom and revolving around axis 2. Holes 3 are pierced through its shell. Cylinder 1 is surmounted by a metal case 4, the bottom of whose compartments 5 and 6 exactly fit to the external shape of cylinder 1, only leaving a space of about one and one-half millimeters depth along the perforated part of the cylinder-shell, such space constituting a passage for 85 the sliver. The bottom of the compartments 5 and 6 is pierced with holes or slits. Compartment 5 receives steam through pipe 7, while compartment 6 is connected with a reservoir of water under pressure. The case 4 hangs from a pivot 9, which prevents it from 90 being turned by the revolving cylinder 1, toward which it is pressed by the weight 8. Within the hollow cylinder is a perforated 95 100

pipe 10, which also receives water under pressure and whose perforations correspond to those of compartment 6 of the case 4.

In case the sliver is to be impregnated with expensive dyes the injector whereby this operation is to be carried out takes the form shown by Figs. 8 and 9, in which 11 is a metal trough, 12 a metal cylinder, like cylinder 1, Figs. 6 and 7. 13 is a case similar to 4, but 5 having only one compartment connected with a steam-pipe. 14 is a cylinder of the same diameter as 12, having overhanging bars 15 and having its axis somewhat higher than that of cylinder 12. 16 is a solid cylinder of the same 10 diameter as 12 and 14 and having its axis still higher than that of cylinders 12 and 14. The cylinders 16, 12, and 14 revolve almost in contact with and impart motion to each other by means of spur-wheels 17. A floating body 15 (not shown in the drawings) keeps the trough filled with dye-bath up to a level 18, slightly higher than the lowermost edge of case 13.

Wringing out.—This operation is carried out by means of pairs of wood rollers, one of 20 which—namely, the upper one—is coated with rubber.

Dipping into the dye-bath.—The apparatus by means of which the sliver is dipped into the dye-bath and impregnated therewith consists of a small trough 19, Figs. 10 and 11, capable of revolving around the axis 26 and communicating by means of a pipe 21 with a floating body 20, Figs. 1 and 2, supplying it with dye-bath flowing from the tanks 60, Figs. 30 35 1, 2, 3, and 4, and kept at a constant level. A cylinder 22, Figs. 10 and 11, fitted with bars at its surface and similar to 14, Fig. 8, is revolving within the trough 19. The upper cylinder 23 is either hollow and perforated or 40 provided with very thin longitudinal flutes at its surface. It has the same diameter as 22 and revolves almost in contact with the same, but at a higher level. Cylinders 22 and 23 also gear with each other by means of 45 spur-wheels 17.

24 is a guide-roller, and 25 a squeezing or wringing-out roller.

Both the trough 19 and the bar-cylinder 22 are adapted to revolve around axis 26 and 50 are kept into contact with 23 by means of the springs 27, connected with the machine-frame, said springs being intended to prevent breakages in the case of the slivers getting entangled around either 22 or 23.

55 28 is a tube or sleeve surrounding the axle of cylinder 22 and preventing the fibers, which may float in the dye-bath, from being wound round the said axle during its rotation.

In lieu of bar-cylinders 14, Figs. 8 and 9, 60 and 22, Figs. 10 and 11, hollow cylinders pierced with holes or fitted at their surface with large longitudinal flutes or pairs of front disks connected with longitudinal bars like squirrel-cages may also be used.

65 *Conveying and collecting the sliver.*—The conveying and collecting apparatus consists of a metal vessel, Figs. 12, 13, 14, preferably

U-shaped, the upper portions of the U-stems being strongly inclined to the vertical. Each side of the vessel is provided with slots 30, 70 Fig. 14. A continuous rubber belt 31, whose stiffness in transverse direction is secured by wooden cross-slats 37, engaged with the ends of said cross-slats 37 in the slots 30, passes around the rollers 32 and 33 and takes 75 its way outside on the tightening-rollers 39. The vessel is fitted with a removable lid 36 and may be heated by steam through pipe 38. The vessel may also be heated by means of a steam-coil or a double bottom. This 80 conveyer materially differs from that covered by my former patent, No. 705,856, in that it is fitted with one instead of two guiding-belts, whereby all inconveniences arising from the stoppage of one of them or a difference in 85 their speeds are avoided.

34 and 35 are rollers by which the sliver is caused to regularly accumulate on the belt 31.

The general arrangement of the machine.—The machine consists of a number of sections 90 quite similar to each other, whose number only depends on the number of dye-baths which the sliver is to pass through. Four sections are sufficient in most cases, and they are shown as I, II, III, IV in Figs. 1, 95 2, 3, 4 of the accompanying drawings. Section V, Figs. 1, 2, 5, is only intended for washing, wringing out, and finally winding the slivers when dyed. The slivers take a zig-zag path through the various sections, which 100 are connected with each other by means of the collecting and conveying apparatus 40 41 42 43. The driving-shaft 44 is mounted at the upper part of the machine in a direction perpendicular to that of the various sections. 105 The same is driven by means of a fast and loose pulley 45 and causes the various parts of the machine to revolve through chain-pulleys 46, mounted on couplings 48, Fig. 15, fitted with clutches 49, arranged for disengaging. Each 110 section may therefore be stopped without interfering with the other ones. Each coupling is fitted with a self-acting disengaging device 50, putting the corresponding section out of action in the case of undue resistances arising in order to prevent possible breakages. On the longitudinal joists of the different sections the different parts are arranged as follows:

Section I, Fig. 3: (a) A stop-motion R, of 120 any well-known construction, which puts the whole section out of action should a sliver get broken; (b) an impregnating device S, like one of those shown in either Figs. 6 and 7 or Figs. 8 and 9; (c) a pair of wringing-out rollers P; 125 (d) a device U for dipping the sliver into the dye-bath, like that shown in Figs. 10 and 11; (e) a revolving reel 52, with flexible arms designed to arrange the slivers in folds.

Sections II, III, and IV, Fig. 4, consist of 130 (a) one or two pairs of wringing-out rollers P, (in the case of such pairs of rollers being two in number a water-jet G for the purpose of washing is interposed between the first pair

and the second one;) (b) dye-bath trough U; (c) reel for arranging the sliver in folds.

Section V, Fig. 5, consists of (a) wringing-out rollers P, with water-jets G for the purpose of washing; (b) winding apparatus.

The working of the machine is as follows: Six or seven card-pots are set before the feeding end of section I. The slivers contained therein pass along a guide-plate on the stop-motion R, Figs. 16 and 17, consisting of blades 53, journaled at their middle, spoon-shaped at one end, while from the other end thereof hangs a plate 54, provided with a recess. As long as the spoon-shaped end is being held down by the tension of the sliver gliding thereon the continuously-revolving blade 55 is free to enter the recess of plate 54; but as soon as the sliver breaks the weight of the plate 54 causes the blade 53 to turn, 20 and the plate 54 falls down, whereby the part which has no recess is brought opposite the blade 55, which on revolving shifts lever 56 toward the left and removes the stop 57, whereupon the weight 58 is allowed to fall 25 down and draws with it the starting-lever 59, Fig. 3, causing the whole of the section to stop at once. On leaving the stop-motion the slivers pass to one of the impregnating devices S. (Shown in either Figs. 6 and 7 or Figs. 8 and 9.) 30 In the first case they enter the space between the perforated cylinder 1 and the case 4. The sliver resulting from the coupling of six or seven elementary slivers following the motion imparted to it by cylinder 1 is struck first by 35 the jet of the steam flowing through 5, which expels all the air from the fibers, and later on by the jets of water flowing through both 6 and 10, which condense the steam and leave the fibers thoroughly impregnated with liquid. 40 If the impregnating device resorted to is of the description shown, Figs. 8 and 9, the slivers after having passed between 12 and 13, whereby the air is thoroughly expelled by the steam-jet flowing through 13, are wound 45 round the bars-cylinder 14 and compelled to dip into the dye-bath, which condenses the steam, takes its place, and thoroughly impregnates the slivers. On leaving cylinder 14 the sliver goes on to cylinder 16, by which 50 it is delivered to the wringing-out rollers. The level of the liquid within the trough 11 must be such as to cover the edge 18 of case 13 in order to prevent fresh air from again entering the fibers of the sliver, and to allow 55 the same to get fully impregnated with liquid. On leaving the wringing-out rollers the sliver is sufficiently tough to admit of its going over to the roller-guide 24 of the dipping apparatus U, Fig. 10, wherefrom it proceeds to 60 the bars-cylinder 22, which dips it into the dye-bath and delivers it to cylinder 23 when the roller 25 has wrung out the liquid in excess. On leaving cylinder 23 the sliver, by means of reel 52, is arranged in regular 65 layers or folds between the rollers 32 and 34 on belt 31 of the conveying device, Fig. 12. 47, Figs. 3 and 4, is an oscillating plate con-

trolled by the reel, the function of which is to press down the folds of the sliver as arranged by the reel in order to obtain a regular pile of folds. The slow motion of the continuous belt 31 as controlled by the rollers 32 and 33, driven by chains and endless screws in any known manner, causes the cotton collected upon the belt to proceed 70 toward the succeeding section. During said passage the dye fastens on the cotton, which may be meanwhile steamed. On reaching the opposite end of the vessel—namely, the rollers 33 and 35—the sliver is drawn in by 75 the wringing-out rollers of section II, whereupon it proceeds to a second dipping apparatus, which may be preceded by the action of a second pair of wringing-out rollers, a water-jet G, Fig. 4, being always interposed 80 between two adjacent pairs of wringing-out rollers.

The operations set forth above go on in sections II III IV until the sliver reaches section V, Fig. 5, when proper water-jets G and pairs 90 of wringing-out rollers perform the last steps of the treatment. The sliver when finally wrung out is passed to the pulleys 61 62, Fig. 5, whereby it is wound on a core 63, which is kept in contact with said pulleys 95 both by its own weight and by the weight of two metal disks 64, one of which—namely, the front one—may be removed with the view of drawing out the sliver-finished rollers, (cheeses,) which serve as a guide to the 100 rollers which are being formed. The whole is conveniently counterbalanced, so as to control the pressure under which the sliver-roller has been formed.

Having now described my invention and 105 how the same is performed, what I desire to protect by Letter Patent is—

1. A device for impregnating slivers, comprising a perforate rotatable cylinder, a hollow case mounted adjacent to and resting 110 upon the cylinder and provided with a perforated bottom, means for conducting the impregnating fluid to the case, and means for rotating the cylinder and for causing the slivers to be fed between the case and cylinder. 115

2. A device for impregnating slivers, comprising a perforate rotatable cylinder, a hollow case mounted adjacent to and resting by gravity upon the cylinder and provided with a perforated bottom, means for conducting the 120 impregnating fluid to the case, and means for rotating the cylinder and for causing the slivers to be fed between the case and cylinder.

3. A device for impregnating slivers, comprising a perforate rotatable cylinder, a hollow case mounted adjacent to and resting upon the cylinder and provided with a perforated externally-concave bottom, means for conducting the impregnated fluid to the case, and means for rotating the cylinder and for causing the slivers to be fed between the case and cylinder. 125 130

4. A device for impregnating slivers, comprising a perforate rotatable cylinder, a hol-

low case mounted adjacent to and resting upon the cylinder and provided with an externally-concave bottom having a channel formed therein for the reception of the slivers, means for conducting the impregnated fluid to the case, and means for rotating the cylinder and for causing the slivers to be fed between the case and cylinder.

5. A device for impregnating slivers, comprising a perforate rotatable cylinder, a hollow multichambered case mounted adjacent to and resting upon the cylinder and provided with a perforated externally-concave bottom, means for conducting steam and 10 water to the respective apartments of the case, and means for rotating the cylinder and for causing the slivers to be fed between the case and cylinder.

6. A device for impregnating slivers, comprising a perforate rotatable cylinder, a hollow case mounted adjacent to the cylinder and provided with a perforated bottom, a case located within the cylinder and provided with a perforated externally-convex wall, the perforations registering with those of the first 20 casing, means for conducting the impregnating fluid to the two casings, and means for rotating the cylinder and for causing the slivers to be fed between the first-named case and the cylinder.

30 7. A device for impregnating slivers, comprising a perforate rotatable cylinder, a hollow multichambered case mounted above and resting upon the cylinder and provided with a perforated externally-concave bottom, a second case disposed within the cylinder in fixed 35 relation to the first case and having an externally-convex perforated wall, the perforations of the second case registering with those of the opposing compartment of the first-named case, means for conducting steam to one of the compartments of the upper case, and means for conducting water to the second case and the opposing compartment of the 40 upper case, and means for rotating the cylinder and for causing the slivers to be fed between the upper case and cylinder.

45 8. A device for impregnating slivers, comprising a perforate rotatable cylinder, a hollow multichambered case mounted above and resting upon the cylinder and provided with a perforated externally-concave bottom having a channel formed therein for the reception 50 of the slivers, a second case disposed within the cylinder in fixed relation to the first case and having an externally-convex perforated wall, the perforations of the second case registering with those of the opposing compartment of the first-named case, means for conducting steam to one of the compartments of the upper case, and means for conducting water to the second case and the opposing compartment of the upper case, and means for rotating the cylinder and for 55 causing the slivers to be fed between the upper case and cylinder.

60 9. A device for impregnating slivers, com-

prising in combination a tank, a perforate cylinder mounted to rotate therein, a hollow case mounted adjacent to and resting upon the cylinder and provided with a perforated externally-concave bottom, means for conducting the impregnating fluid to the case, means for causing the cylinder to be fed between the case and cylinder, a second perforate cylinder 70 mounted within the tank adjacent to the first cylinder and serving as a drum to receive the slivers therefrom, a third cylinder rotatably mounted adjacent to the tank and adapted to receive the impregnated slivers, means for rotating the cylinders, and means for maintaining the impregnated fluid in the tank at 75 a desired level.

10. A device for impregnating slivers, comprising in combination a tank, a perforate rotatable cylinder mounted therein, a hollow case mounted above and resting upon the cylinder and provided with a perforate externally-concave bottom having a channel formed therein for the reception of the slivers, means for conducting steam to the case, means for causing the slivers to be fed between the case and cylinder, a second cylinder within the tank and having its surface formed of spaced bars, the second cylinder geared to rotate with 80 the same peripheral velocity as the first cylinder and serving as a drum to receive the slivers therefrom, a third cylinder rotatably mounted adjacent to the tank and adapted to receive the impregnated slivers, means for 85 rotating the cylinders, and means for maintaining the impregnated fluid in the tank at 90 such a level as to partially submerge the perforate cylinders.

11. A device for dyeing slivers, comprising a tank, a cylinder mounted to rotate therein, a guide leading the slivers to the cylinder, a second cylinder mounted adjacent to the first cylinder and geared therewith, a compression-roll mounted adjacent to and bearing upon 105 the second cylinder, and means for imparting motion to the cylinders.

12. A device for dyeing slivers, comprising a tank, a perforate cylinder mounted to rotate therein, a guide-roll leading the slivers to the 110 cylinder, a second cylinder mounted adjacent to the first cylinder and rotating therewith, a compression-roll mounted adjacent to and exerting yielding pressure upon the second cylinder, and means for imparting motion to 115 the slivers.

13. A device for dyeing slivers, comprising a tank, a cylinder having its surface formed of spaced bars and mounted to rotate therein, a second cylinder mounted adjacent to the 120 first cylinder, and rotating therewith, a compression-roll mounted adjacent to and exerting pressure upon the second cylinder, and means for imparting motion to the cylinders.

14. A device for dyeing slivers, comprising a tank, a cylinder having its surface formed of spaced bars and mounted to rotate therein, a guide leading the slivers to the cylinders, a second cylinder mounted adjacent to the first 130

cylinder and rotating therewith, yielding means for holding the second cylinder in connection with the first cylinder, a compression-roll mounted adjacent to and exerting yielding pressure upon the second cylinder, means for imparting motion to the cylinders, and means for maintaining the dye within the tank at a desired level.

15. The combination, with a series of tanks, of means for transferring the slivers from one to the other, consisting of a frame substantially U-shaped in both longitudinal and cross section, and having double walls, said frame provided with interior flanges forming guiding-slots, suitable pulleys mounted upon the frame, an endless belt passing over said pulleys and through said guiding-slots, guide-pulleys adjacent to the extremities of the endless belt, means for supplying a heating medium to the space between the double walls; means for actuating the pulleys, and means for laying the slivers upon the belt in folds.

16. The combination, with a series of tanks, of means for transferring the slivers from one to the other, consisting of a frame substantially 25 U-shaped in both longitudinal and cross section, and having double walls, said frame provided with interior flanges forming guiding-slots, suitable pulleys mounted upon the frame, an endless belt passing over said pulleys and through said guiding-slots, guide-pulleys adjacent to the extremities of the endless belt, means for actuating the pulleys, means for laying the slivers upon the belt in 30 folds, and means for covering said frame in such a manner as to constitute a chamber, and means for supplying steam to the space between the double walls of the chamber.

In testimony whereof I affix my signature in presence of two witnesses.

DIEGO MATTEI.
